UNITED STATES PATENT OFFICE.

ALBERT E. HUTT, OF ARDMORE, PENNSYLVANIA.

VALVE-STEM SILENCER.

Application filed July 5, 1923. Serial No. 648,466.

To all whom it may concern:

Be it known that I, ALBERT E. HUTT, a citizen of the United States, residing at Ardmore, county of Montgomery, State of Pennsylvania, have invented new and useful Valve-Stem Silencers, of which the following is a specification.

In the valve-in-head, T head, L head and the general type of gas engines of the foregoing conventional character now in vogue in automobiles, trucks, self propelled vehicles and the like, the outer end of the rocker arm or valve actuator which coacts with the valve stem to unseat the valve at the proper periods usually impacts directly thereon, with a tappet action which results in an unnecessary amount of noise, and wear, which by my invention, I have practically eliminated, and in addition by my novel construction the rocker arm and valve tend to function as a unit, so that the control of the valvular functions of the valve is rendered more positive and effective than heretofore.

To the above ends, my invention consists of a novel construction of connecting devices common to the free end of the rocker arm and valve stem comprising a pair of juxtaposed contacting discs, whereby noise and wear are practically eliminated and no lost motion is present during the unseating or actuation of the valve and its adjuncts.

It further consists of a novel construction of a ball and socket or universal joint connection in combination with a pair of discs common to the rocker arm and valve stem.

It further consists of a novel manner of securing in position and assembling the ball and socket connection common to the rocker arm and valve stem and its adjuncts and a novel means for locking in the various desired adjusted positions the nut or threaded plug which holds the parts in position.

It further consists of novel means for keeping the various parts properly lubricated and for retaining an adequate supply of the lubricant between the contiguous coacting surfaces of the connections, common to the rocker arm and juxtaposed valve stem.

It further consists of a novel manner of constructing the end of the rocker arm so that the various parts can be expeditiously and accurately assembled.

For the purpose of illustrating my invention, I have shown in the accompanying drawings forms thereof which are at pres-

ent preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a valve stem silencer embodying my invention, and a portion of an internal combustion engine to which the same is applicable.

Figure 2 represents on an enlarged scale a plan view of my novel rocker arm, the outer end being in section on line 2—2 Figure 3.

Figure 3 represents a section on line 3—3 Figure 2.

Figure 4 represents a front view of Figure 2 with the spherical seat removed.

Figure 5 represents a section on line 5—5 Figure 4.

Figure 6 represents a plan view of a portion of Fig. 3.

Figures 7 to 9 represent vertical sections of modifications.

Figures 10 and 11 represent side and end views of cams employed. Figures 12 and 13 represent modifications.

Similar numerals of reference indicate corresponding parts.

Referring to the drawings.

It will be understood that my invention is applicable to any of the forms of tappet actuated valves in the valve-in-head, T head or L head internal combustion engines, of the conventional type and I have shown in Fig. 1, one form of a conventional, internal combustion engine 1 having the cam shaft 2, lifting rod 3, bracket 4, valve 5, valve stem 6 and valve spring 7 all of which elements and their mode of operation are well known and need not be described in further detail, as my present invention relates more particularly to the novel construction of the outer end of the rocker arm 8 and the novel ball and socket or universal joint connections common thereto, and to the contacting discs of the upper end of the valve stem 6, said rocker arm being fulcrumed in the bracket 4 in the usual manner.

The outer end of the rocker arm is internally threaded at 9 and provided with the threaded plug or closure 10, whose bottom contacts with the block 11 having the con-

cave bottom wall 12 said block resting on the split plate 13, which rests on the bottom shoulder or wall 14 of the chamber 15.

It will be understood from the foregoing, 5 that the rod 3, the rocker arm 8 and its adjuncts serve as a valve actuator.

The plate 13 has a curvilinear seat therein, forming a continuation of the concave or hemispherical wall 12, so that when the 10 parts are assembled as seen in Fig. 3, a substantially spherical seat or socket is formed for the spherical head 16, of the member 17, which has the shank 18 rising from the disc or base flange 19.

15 The bottom of the disc 19, rests upon the top 20 of the pan shaped member or disc 21, which is supplied with lubricant and provided with the upper peripheral flange 22 which retains said lubricant, and the 20 lower peripheral flange 23, which engages the upper portion of the valve spring 7.

The bottom of the disc 19 is provided with a small central oil reservoir or pocket 24 and the bottom of the member 21 is provided with a seat 25, whose walls 26 engage the upper end of the valve stem 6 which is fastened thereto by the transverse pin 27. The nut or threaded plug 10, is provided with a plurality of diametric milled slots 28, whose terminals may align with the holes 29 in the outer portion 30 of the rocker arm, so that when the desired slot 28 is in alignment with the desired hole 29, a cotter pin 33 can be inserted therethrough to lock said 35 nut or plug from rotation.

For convenience in assembling, I provide an opening 31 in the front of the rocker arm 8, whose front wall extends above the shoulder 14, as seen at 32 in Figure 4, so 40 as to retain the split plate 13 in position.

The operation is as follows:—

As the rocker arm or valve actuator is oscillated on its fulcrum, it will through the medium of the ball and socket or universal 45 joint connection, instantaneously unseat the coacting valve, which latter is seated or moved upwardly by the tension of the valve spring. The slight space between the contiguous upper and lower discs, which in 50 practice is about .004 to .001 of an inch and affords the necessary play between the parts is in practice occupied by a thin film of oil or any other substance including air and there is consequently no noisy tappet action 55 present, as is the case when the rocker arm impacts directly on the upper end of the valve stem, so that my device when in use is practically noiseless.

It will be understood in the practical 60 operation of my invention, that when the valve 5, as seen for example in Figure 1, is seated, there is a very slight amount of play away from the disc 21 allowed for the valve actuator and the upper disc 19 when 65 the engine is cold or initially started. When

the rocker arm 8 or the valve actuator moves inwardly to unseat the valve, the juxtaposed areas of the discs 19 and 21, will then be in pressure contact except for the intervention of a very thin film of the lubricant or silencing medium. The presence of this film obviously obviates or reduces to a minimum all noise caused by the contact of said juxtaposed areas, and as the engine continues to run and heats up, the clearance between these juxtaposed areas gradually lessens. I have found in practice that there is at all times present, more or less of a thin film of the lubricant or silencing medium between said juxtaposed areas and the latter are thus obviously in pressure contact with the silencing medium at the period of unseating the valve.

It will be apparent from the foregoing that my novel device constitutes a species of ball and socket or universal joint connection common to the end of the rocker arm and the juxtaposed valve stem in conjunction with the upper and lower discs whereby lost motion is eliminated, the functioning of the valve at the proper periods is positively provided for in synchronism with the rocker arm and the thin film of lubricant between the contiguous coacting areas of the upper and lower discs will not only afford 90 an adequate supply of the lubricant for the proper lubrication of the contiguous parts at all times but will in addition serve to deaden all noise.

The ball and socket or universal joint connection permits the proper limited play to the coacting elements which is necessary by reason of the oscillatory or rocking motion imparted to the rocker arm and the range of adjustment afforded by the threaded plug and its locking devices enables all the parts to be quickly assembled and properly adjusted.

It will further be seen from the foregoing that the two disc like members, 19 and 21 perform an important function in my novel organization, since by reason of their contacting juxtaposed surfaces, I am enabled to effect the desired synchronous reciprocations of the coacting valvular elements, and in conjunction with the upper disc 19, I may employ other equivalent forms of ball and socket members slightly different from that shown.

It is obvious that while I have shown my invention in Fig. 1 as applied to an upwardly seating valve, it can be used with equal facility and advantage with a downwardly seating valve, as seen in Figs. 7 to 9, and it can be applied to inlet or exhaust valves 125 or both as may be desired.

In Figs. 8 to 9, 34 designates a downwardly seating valve having my invention applied thereto, 35 designating the valve stem movable in the guide 36 at the lower end of 130

the valve stem which is pinned to the upper disc 36^a, having the outer peripheral flange 37 engaging the lower end of the spring 38.

The bottom of the disc 36^a is juxtaposed to or in contact with the top surface of the bottom disc 39, which is provided with the peripheral upwardly extending flange 40. The lower disc 39 has the ball and socket or universal joint connection 17, which conforms to the construction seen at 17 turned upside down and which need not be redescribed, said connection being mounted on the yoke 41, whose lower end is engaged by the rod or valve tappet 42, whose lower end is secured to the U shaped yoke or frame 43.

44 designates the cam shaft, which carries the cams 45 and 46, the contour of whose working faces will be apparent from Fig. 10, it being apparent that one cam serves to 20 actuate the rod 42 and its adjuncts in one direction, while the other cam serves to actuate said rod and its adjuncts in the opposite direction, the valve being positively actuated in both directions smoothly and 25 noiselessly.

In the construction seen in Figure 9, I employ the upper and lower discs 37 and 39 seen in Figure 8 but attach to the bottom of the lower disc the housing 47 containing the bearing plates 48 and 49 carrying the ball 50 which is the upper end of the rod 42.

It will be seen that in all the embodiments of my invention, the discs, plates or their equivalents having their surfaces in contact 35 as described are an essential element in the organization and contribute most efficiently to the noiseless and effective operation of the valvular mechanism in synchronism with the other coating elements.

40 The small oil reservoir 23, seen in Figures 3, 4, 8 and 9 may be located in the lower disc, if desired, or left out entirely, as is evident. I have deemed it unnecessary to describe in detail the cycle of operation of the engine seen in Fig. 7, as this will be apparent to those skilled in this art. The ball 16 can be lubricated by any suitable means as by the ports 51, seen in Figure 3.

45 It will be understood that while I have shown the abutting surfaces of the members 19 and 21 as being disc shaped and have so described them, I may employ other or equivalent polygonal shapes or if desired I may employ the constructions seen in Figures 12 and 13. In Figure 12, the upper and lower contacting members are conical and designated as 52 and 53 while in Figure 13, I have shown the contacting surfaces as being convex at 54 and concave at 55, the other coating elements as the ball and socket and the valve stem and their adjuncts being of the same construction as already described. In the construction seen in Figures 12 and 13, I prefer to have the

juxtaposed surfaces so positioned with respect to each other that a thin film of the silencing medium will be present, as indicated in Figure 3, but it will be evident that in all the embodiments of my invention, the 70 juxtaposed surfaces of the disc-like members or their equivalents may be substantially in contact without departing from the spirit of my invention.

It will now be apparent that I have devised a new and useful valve stem silencer which embodies the features of advantage enumerated as desirable in the statement of the invention and the above description, and while I have, in the present instance, shown and described preferred embodiments thereof of which will give in practice satisfactory and reliable results, it is to be understood that these embodiments are susceptible of modification in various particulars without 80 departing from the spirit or scope of the invention or sacrificing any of its advantages.

Having thus described my invention what I claim as new and desire to secure by Letters Patent, is:—

1. In a silent valve operating mechanism, a rocker arm, a valve, a stem for said valve, a disc shaped member attached to and movable with said rocker arm, a joint common to said rocker arm and its disc, a second disc shaped member attached to said valve stem, the juxtaposed substantially contiguous areas of each disc being greater than the area of said valve stem, and a film of silencing medium interposed between and contacting with said juxtaposed areas, which latter are in contact with each other, except for the intervention of said silencing medium.

2. In a silent valve operating mechanism, a rocker arm, a valve, a valve stem, a plurality of members having enlarged surfaces intermediate said rocker arm and stem, whose juxtaposed areas are each greater than the cross sectional area of said valve stem, a film of lubricant interposed between and in contact with said juxtaposed areas, which are in contact except for the intervention of said film, said film being compressed when said members are actuated to unseat said valve, a lubricant pocket in one of said areas, a universal joint intermediate one of said members and said rocker arm, and a spring bearing on one of said members, for holding said valve normally seated.

3. In a silent valve operating mechanism, a valve actuator, a valve, a valve stem; a plurality of members intermediate said actuator and valve stem, whose juxtaposed areas are greater than the area of said valve stem, a lubricant pocket for one of said areas, an annular flange on one of said members for the retention of the lubricant, a film of the latter being interposed between 130

said juxtaposed areas, said film being compressed between said members, when the latter are actuated to unseat said valve, and a universal joint intermediate said valve actuator and its member.

4. In a valve stem silencer, a rocker arm, a detachable socket in the end of said rocker arm, a ball in engagement with said socket, an upper disc carried by said ball, a valve 10 stem and lower disc carried by said valve stem, the juxtaposed surfaces of said discs being in contact, when actuated, with a silencers medium, a lubricant reservoir in one of said discs, and an upper peripheral 15 flange on said lower disc for retaining lubricant thereupon.

5. In a valve stem silencer, a rocker arm having a detachable socket therein formed of a plurality of members, a threaded plug 20 engaging the upper of said members for locking said socket in the desired position, a ball engaging said socket, a valve stem and contacting discs carried by said ball and valve stem.

25 6. In a valve stem silencer, a rocker arm

having a detachable socket therein formed of a plurality of members, a threaded plug engaging the upper of said members, means for locking said plug in the desired position, a ball engaging said socket, and connections 30 intermediate said ball and valve stem, said connections comprising a plurality of discs having their juxtaposed surfaces in contact, when actuated, with silencing medium.

7. In a valve stem silencer, a rocker arm 35 having a detachable socket therein formed of a plurality of members, a threaded plug engaging the upper of said members, means for locking said plug in the desired position, a ball engaging said socket, and connections 40 intermediate said ball and valve stem, and comprising discs in contact, when actuated, with a silencing medium and a peripheral flange on one of said discs for retaining the silencing medium.
